UNITED STATES PATENT OFFICE.

RICHARD MULHOLLAND, OF DUNKIRK, NEW YORK.

VEHICLE-SPRING.

SPECIFICATION forming part of Letters Patent No. 296,347, dated April 8, 1884.

Application filed May 31, 1882. (No model.)

To all whom it may concern:

Be it known that I, RICHARD MULHOLLAND, a citizen of the United States, residing in Dunkirk, in the county of Chautauqua and State of New York, have invented certain new and useful Improvements in Vehicle-Springs, of which the following is a specification.

My invention relates to certain improvements in vehicle-springs, which will be fully 10 and clearly hereinafter shown by reference to the accompanying drawings, in which—

Figure 1 represents an under or bottom view of a vehicle, showing a similar view of my invention. Fig. 2 is a side elevation of the 15 same. Fig. 3 is an end view; and Figs. 4 and 5 are detached views, showing modified ways of constructing a portion of the torsion-springs.

The object of my invention is to produce a device that will at all times work easy 20 without binding or cramping, and at the same time permit the body of the vehicle to pass downward and upward, either above or below the plane of the end leaf-springs.

A represents the body of a vehicle, having 25 at its front and rear ends the usual end leaf-springs, or a spring-bar or its equivalent. The torsion-springs C are preferably made in pairs, a pair being connected to each end of the vehicle, as shown; but, if desired, the springs 30 may be formed from a single bar or rod, substantially as shown in Figs. 4 and 5. The springs C (see Fig. 1) are bent at their ends to form the arms a, which are secured, in the usual way, by bolts at the ends and an eye- 35 piece or staple, or in any other well-known way, at the point where the bend is. The portions of the springs which are subjected to torsion are secured to the body A by bearing- plates b, so that while firmly held in place 40 they are allowed to turn or twist. At the outer ends of the springs C are curved arms G, formed by bending them in an outward direction, substantially as shown at c. They are then bent in a forward direction, (see Fig. 1,) 45 and are again bent outward in the direction of the length of the end leaf-springs or bars, thereby forming the parts d, which are secured to the ends of the leaf-springs E, or to the end bars, D, so that the portion d extends under 50 and in a line with the longitudinal center of the springs E or bars, and are secured by bolts e. It will be seen from this construction that

while the parts d are directly under and in a line with the springs e, the parts e and G are outside of the springs, or between the ends of the body A and the leaf-springs or bars, so that the body can move freely past the springs, either down or up.

The object in connecting the torsion-springs to the end leaf-springs by the portions d, extending in the same direction with a line drawn through the longitudinal center of the spring E, is to prevent the cramping or bending of the same. If the torsion-springs were bent so as to pass through a hole directly across 60 the ends of the leaf-spring or bar, it will be readily seen that the outer ends of the springs would bend first or bend the easiest, and thereby bind in the journal or opening through which it passed, and in so bending it would 65 not only become tight in the journal, and refuse to act properly, but it would also bend or twist the spring or bar to which it is attached out of shape, and thereby injure or partly destroy both of them, and thus prevent 70 their practical operation. One of the objects of my invention is to overcome these objections.

When leaf-springs E are used in connection with the torsion-springs C, the pressure of the load upon the latter will be equal to that upon 80 the leaf-springs, and cause both springs to lengthen or shorten equally the distance between their extremes, and thereby permit both to adjust themselves to the downward and upward action of the body of the vehicle. 85

The portions d of the arms G are shown as being attached directly to the leaf-springs by means of a pivot or bolt at e; but they may also be attached as shown in Fig. 3, where the parts d are connected to a shackle, F, the 90 ends being pivoted by a pin, f, thereby allowing for the movements of the ends of the springs to or from each other, produced by the downward and upward movement of the body of the vehicle. 95

I claim as my invention—

In a vehicle-spring, the combination, with the body and end leaf-springs or bars, of the torsion-springs having their outer arms bent at right angles (or nearly so) to their length, 100 which arms are provided with an additional bend nearer their ends in a line with the length of the torsion-springs, or substantially so, and with a short bend in the direction of

the length of the leaf-spring or bar, so that the ends of the arms are connected under the center of the leaf-springs, thereby allowing the body of the vehicle to move downward and 5 upward, and pass the plane of the leaf-springs or bars, substantially as and for the purposes described.

In testimony that I claim the above I have hereunto subscribed my name in the presence of two witnesses.

RICHARD MULHOLLAND.
